UNITED STATES PATENT OFFICE

JOHN H. VAN SICKELS, OF MONTREAL, QUEBEC, CANADA, ASSIGNOR TO GENERAL CIGAR COMPANY LIMITED, OF MONTREAL, CANADA

DISPLAY CASE

Application filed June 2, 1926. Serial No. 113,244.

This invention relates to new and useful improvements in display cases and particularly to display cases having a plurality of independently hinged covers, and the object 5 of the invention is to provide a case of the class stated which will have means to efficiently seal the covers when closed and means to hold the covers in their sealed condition, said holding means being so constructed that 10 they may be only operated by the person authorized to do so.

Another object is to provide a case of the class stated which will be simple in construction, attractive and neat in appearance, and 15 efficient as regards preservation of the goods contained therein and the manner of displaying same.

In my invention I provide a display case having a plurality of independently hinged 20 covers formed in such a manner that goods placed within the case will be displayed through transparent material forming the central portions of the covers. The covers are provided with means to position them so 25 that they will engage with spring controlled locking means, comprising a locking lever, each positioned to engage with slots formed in the cover, said locking levers being connected to a bar which when moved unlocks all 30 the covers in unison. The bar is positioned within the case, with one end passing through the back of the case and said end is connected to a cam-shaped lever adapted to hold the locking levers in their locked or unlocked 35 position, and against the action of a spring. A slot is cut in the end of the bar, said slot being adapted to engage with the back of the case and a spring is provided to hold the slot 40 in engagement with the back of the box to prevent unauthorized opening of the case covers. Means are provided within the case to position the articles to be vended and means are also provided to keep said articles 45 in good condition, so that they will retain their quality and market value.

In the drawings which illustrate one form of my invention;

Figure 1 is a plan of my improved display 50 case.

Figure 2 is a sectional elevation of the case taken on the line 2—2 Figure 1.

Figure 3 is an enlarged sectional end elevation of one of the covers and the part of the case adjacent thereto showing the sealing 55 means.

Figure 4 is a side elevation of the end of the locking bar in the locked position, and Figure 5 is a side elevation of the end of the lever in the unlocked position. 60

Referring more particularly to the drawings, which illustrate a display case suitable for counter use, 11 designates the bottom of the case, 12 the sides, and 13 and 14 the front and back respectively. The front of the case 65 is made lower than the back so that the upper edges 15 of the sides slope downwardly towards the front. Extending from side to side of the case and attached in any suitable manner to the upper edge 15 of said sides, 70 are the cover supports 16, which are shown in section in Figure 2, and are of channel formation, but this is for illustrative purposes only and these supports may be made of any suitable cross section which will provide 75 downwardly extending legs 16^a for the purpose hereinafter stated. Attached to the cover supports by means of the hinges 17, are the cover frames 18, which are provided with transparent centre portions 19, through which 80 the goods within the case may be displayed. The cover frames are of rectangular formation with grooves 20 formed in the inner faces 21 and the sheets of glass or other transparent material forming the centre portions are 85 held within the grooves by means of the cushioning members 22, which may be made of rubber tubing or like resilient material. Projecting downwardly from the inner edges of the frames are the sealing and positioning 90 ridges 21^a, which contact with downwardly projecting portions of the cover supports and also the downwardly projecting edges 21^b of the sides and ends of the case. A slot 23 is cut or formed in the lower face and in one side 24 95 of each of the frames, so that the hooked ends 25 of the locking levers 26 will pass through said slots and engage with the edges 27 of the slots to lock the covers. The levers 26 are pivotally mounted on brackets secured to one 100

side of the casing and the hooked ends pass through slots formed in said upper edge 15 which is strengthened by being first bent inwardly to form a seat for the cover frame and then downwardly to form an efficient sealing 5 means for the cover as shown clearly in Figure 3. The lower ends 28 of the levers extend beyond the brackets and are coupled together by means of the link or bar 29 pivotally attached to the levers by means of the pins 30, 10 so that on movement of said bar, all the locking levers will move in unison. Pivotally attached to, and in close proximity to one end of the link is the connecting rod 31, one end 31^a of which is adapted to pass through a slot or aperture formed or cut in the back of the casing. An operating handle 33 is pivotally attached to the end of the connecting rod by means of the pin 34. The handle is so formed 15 that the distance between the centre of the pin 34 and the surface 35 is less than the distance between said centre and the surface 36, so that the handle when turned or rotated on the pin 34 will pull the connecting rod towards the back of the box thereby operating 20 the locking levers through the attached link. A collar 37 may be secured to the connecting rod and a spring 38 surrounding said rod may be placed between the collar and the inner 25 surface of the back of the case. A notch 32^a may be cut in the connecting rod in such a position that when the locking levers are in the locked position that is engaging with the closed or sealed lids, said notch will engage 30 with the back of the case and prevent movement of the rod. The notch is shown cut in the upper edge of the lever, so that the hand lever must be pressed downwardly to unlock the covers. A spring 32^b 35 may be provided to hold the notch in the rod in engagement with the back of the case, said spring being attached at one end to the bracket 32^c, secured to the back of the case by any suitable means, while the other 40 end of the spring is secured to the spring 38 or to the rod, or to any other part movable with the rod. A plurality of spaced supports 39 may be secured to the inner surface of the bottom of the box and they may be made in 45 such a manner that their upper surfaces 40 lie parallel with the upper edges of the sides of the casing, so that boxes of cigars, cigarettes, or the like, will be held in such a manner that their contents will be displayed to 50 the best advantage. Guides 41 may be secured or formed in the inner surface of the bottom of the box and slidably mounted in said guides is the humidor 42, which is so constructed that it will slide through a slot 43 55 formed in the back of the casing. The end of the humidor has a thin sheet of metal projecting above and below the main body of the humidor, so that when in position the slot will be covered to prevent escape of the moistened 60 air within the casing. To hold the humidor 65

in position a bracket 44 is secured to the back of the case in proximity to and below the bottom of the slot 43, so that the piece of metal projecting downwardly from the humidor will fit in a space 45 formed between the bracket and the back of the casing. It will be noticed that the front and back having their upper edges formed similar to the sides so that the downwardly projecting piece of the cover will engage therewith and form a seal. 75

Modifications may be made in the general construction of the details of the case without departing from the spirit of the invention. The humidor may be of rectangular formation and made from channel shaped members 80 46, between the flanges of which is placed absorbent material 47 and to hold the material 47 in place, perforated sheets 48 may be mounted between the members 46. 85

In operation boxes of cigars, cigarettes or the like, are placed on the upper edges of the supports and the sides of the boxes are held in place by coming in contact with the vertically disposed portions of the upper edges 90 of the case or cover support. The covers are then closed by dropping them so that the downwardly turned edges of the cover frame will engage with the vertically disposed portions of the side walls and the back, or front 95 or cover supports to seal the cover and prevent escape of the moistened air within the casing. In dropping, the edges of the slots contact with the curved ends of the locking levers, and cause same to move against the spring on the connecting rod until they spring into locking position, when the handle and rod are depressed and the sides of the slot clear of the case. The covers can only be opened by operating the cam lever and this lever must first be pressed downwardly to take the rod slot clear of the back of the casing to allow the cam lever when turned to pull the rod 100 towards the back of the case. 105

It will be seen that a case, constructed in 110 the manner disclosed, cannot be opened except by an authorized person and one familiar with the construction of the case. The lever is placed at the back of the case so that it will have to be operated from the back of the counter on which it is placed. It will also be seen that one or all of the covers can be opened if so desired. The case is so constructed that the goods contained therein may be displayed to the best advantage and by providing humidors within the casing, the quality of the 115 cigars is retained. 120

Having thus described my invention, what I claim is:-

1. In a display case having a plurality of 125 independently hinged covers, locking means for securing said covers in closed position, means formed in the covers to seal said case and to guide the covers towards the locking means, means positioned at the back of the 130

case and connected to the locking means to unlock the covers in unison, a slot formed in the locking means and engaging with the back of the case to prevent unlocking movement of the lock means, and flexible means to hold the slot in engagement with the case.

2. In a display case having a plurality of independently hinged covers, locking means for securing said covers in closed position, means to position the covers to contact with the locking means and to seal the case to prevent escape of air between the covers and case when they are in the closed position, means connected to the locking means and positioned at the back of the case to hold the locking means in the locked or unlocked position, a slot formed in the locking means and engaging with the back of the case to prevent unauthorized unlocking movement of the locking means, and spring controlled means to hold the slot in the locking direction.

3. A display case equipped with a plurality of covers hingedly connected thereto, each cover having a slot formed in one side thereof, a plurality of hooked levers pivoted to the case with the hooked ends projecting above the case to engage with the slots in the covers, means connecting the levers to cause said levers to move in unison, an operating member, connected to said means and projecting through a slot formed in the back of the case, said operating member being laterally movable in said slot and being provided with a notch in which one edge of the slot is engaged at times to prevent movement of the operating member in one direction, a spring encircling the operating member and confined between the back of the case and a suitable abutment carried by the operating member and a second spring connected between the first mentioned spring and the back of the case and arranged to pull the operating member laterally in a direction to engage one edge of the slot in the aforesaid notch of the operating member.

In witness whereof, I have hereunto set my hand.

JOHN H. VAN SICKELS.
